UNITED STATES PATENT OFFICE.

FRED HENRY ROBERTS, OF SOMERVILLE, MASSACHUSETTS.

DESIGN FOR A CONFECTIONERY-HOLDER.

SPECIFICATION forming part of Design No. 30,012, dated January 17, 1899.

Application filed June 23, 1898. Serial No. 684,305. Term of patent 14 years.

To all whom it may concern:

Be it known that I, FRED HENRY ROBERTS, a citizen of the United States, residing at Somerville, in the county of Middlesex and State of Massachusetts, have invented and produced a new and original Design for Confectionery-Holders, of which the following is a specification, reference being had to the accompanying drawings, forming a part thereof.

10 As shown in the drawings, the leading or material feature of my design consists of a series of holders or supports each of which is rectangular in form, has sides which are parallel with each other, and has an inclined front which rises slightly above the support, and which holders vary in regular order as to height from the forward, which is the lowest, to the rear, which is the highest, substantially as shown in the drawings.

20 In the drawings, Figure 1 is a view in perspective of the confectionery-holder from one side. Fig. 2 is a view in perspective of the said holder from the side opposite that shown in Fig. 1. Fig. 3 is a vertical longitudinal section.

In the drawings, A A' A² represent a series of steps.

B B' represent the sides, the upper edge of each of which is shaped to form steps corresponding to the steps A A' A².

C C' C² are walls in front of the various steps and extending the full width thereof. These walls are slightly inclined from a vertical plane, and the steps are also slightly inclined from a horizontal plane by lifting the rear of the holder or by inclining the steps.

The general effect of the entire design is that of a series of narrow steps arranged one behind the other in regular order and with closed sides, the sides corresponding to the rising of the steps.

Having described my invention, what I claim as new, and desire to secure by Letters Patent, is—

The design for a confectionery-holder herein shown and described.

FRED HENRY ROBERTS.
